UNITED STATES PATENT OFFICE.

THOMAS L. DAVENPORT, OF EVERETT, WASHINGTON.

OIL-BURNER.

1,394,188.

Specification of Letters Patent.

Patented Oct. 18, 1921.

Application filed April 19, 1920. Serial No. 375,164.

To all whom it may concern:

Be it known that I, THOMAS L. DAVENPORT, citizen of the United States, residing in Everett, in the county of Snohomish and State of Washington, have invented a certain new and useful Improvement in Oil-Burners, of which the following is a specification.

My invention relates to improvements in oil burners adapted to burn fluid fuel such as crude oil, kerosene, gasoline or other mineral oil products, the invention relating more particularly to the type of oil burners adapted for installation and operation in the fire-boxes of steam boilers or furnaces and the object of my invention is to provide a burner adapted to be removably attached to the door of the fire box of a boiler or furnace to swing outwardly with the said door when it is opened to facilitate the starting of the same and which is further adapted to be inserted within the fire-box when the door is closed.

Another object is to provide a burner embodying a construction wherein the jets of steam or compressed air under pressure are utilized to create a suction whereby the fluid fuel will be drawn from its source of supply into the mixing chamber of the burner.

A further object is to provide a burner embodying simplicity and economy in construction, that is positive and efficient in operation, that is readily accessible and easily cleaned and that will not readily get out of order.

With the above and other objects in view which will appear as the description proceeds, my invention resides in the novel construction, combination, adaptation and arrangement of parts hereinafter described and claimed.

I accomplish these objects by devices illustrated in the accompanying drawings, wherein—

Figure 1 is a top plan view of an oil burner embodying my invention as it would appear attached to the door of a fire-box, parts being in horizontal section;

Fig. 2 is a view in side elevation of the same, parts being in vertical section;

Fig. 3 is a view in transverse section on broken line 3, 3 of Fig. 1;

Figs. 4 and 5 are views in transverse section on broken lines 4, 4 and 5, 5 of Fig. 2;

Figs. 6 and 7 are views in elevation of two details of my invention; and

Fig. 8 is a view in fragmentary vertical section on broken line 8, 8 of Fig. 2.

Referring to the drawings, throughout which like reference numerals indicate like parts, the burner in its present form comprises the cylindrical sections 10 and 11, a coupling nut 12, end caps 13 and 14, a fluid fuel pipe 15, a fluid fuel control valve 16, a steam or air supply pipe 17, a steam valve 18, tubular members 19 and 20, a connecting nipple 21, an attaching plate 22, a metallic block or base 23, U-shaped fuel conduit pipes 24, a retaining plate 25, and a burner tip 26.

The cylindrical sections 10 and 11 are externally threaded at each of their ends and are connected together by the coupling nut 12 to form a continuous cylindrical casing 75 of the desired length.

The coupling nut 12 is provided with an interiorly centrally disposed annular web or partition 27 having an axial opening 28 adapted to register with the bores of the tubular members 19 and 20 and is also provided with arcuate slots 29 adapted to register with the annular passageway 30 formed by the walls of the sections 10 and 11 and the walls of the tubular members 85 19 and 20.

The cap 13 is threadably engaged on the outer or rear end of the cylindrical casing formed by the sections 10 and 11 and is provided with an outwardly projecting axial boss 31 that is interiorly threaded for the reception of the fluid fuel pipe 15, within which pipe is interposed the fluid fuel control valve 16.

The cylindrical section 10 of the casing is 95 provided with an enlarged chamber 32 having an interiorly threaded boss 33 on one of its sides thereof for the reception of the steam-pipe 17. Interposed in the steam pipe 17 is the steam control valve 18.

Longitudinally and concentrically disposed within the cylindrical casing formed by the sections 10 and 11 are the tubular members 19 and 20, the members 19 having flanges 34 formed on one of their ends 105 and having their opposite ends externally tapered and provided with longitudinally disposed grooves 35, while the members 20 have flanges 36 formed on one of their ends and have their opposite ends internally 110

flared as at 37 to receive the tapered and fluted portions 35 of the members 19 when the members 19 and 20 are assembled as shown more clearly in Fig. 2.

5 To positively retain the tubular members 19 and 20 in their longitudinal and concentric position within the cylindrical casing I have counterbored the ends of the sections 10 and 11 to form seats for the 10 flanges 34 and 36 on the tubular members 19 and 20 which are retained in the said seats by the coupling nut 12, and the end caps 13 and 14 as shown more clearly in Fig. 2.

The flanges 34 and 36 adjacent the partition 27 are provided with arcuate slots 38 which register with the slots 29 in the partition 27 and also with the annular passageway 30.

20 The end cap 14 is threadably engaged on the inner or forward end of the cylindrical casing formed by the sections 10 and 11 and is provided with an outwardly projecting axial boss 39 that is interiorly threaded for the reception of one end of the connecting 25 nipple 21, the other end of which nipple being threadably engaged in a central boss 40 of the attaching plate 22.

The plate 22 is disposed on the outer face of the door 41 of the fire-box, not shown, 30 while the block or base 23 is disposed on the inner face of the door, the plate 22 and block 23 being fixedly secured to the door by cap screws 42.

The door 41 is provided with a hole or 35 aperture 43 which is disposed in axial alignment and registers with the bore of the nipple 21.

40 Registering with the hole 43 is a curved passageway 44 formed in the block 23, which passageway communicates with the leg 45 of the U-shaped conduit pipes 24.

A substantially horizontally disposed semi-circular passageway 46 formed in the block 23 connects the legs 47 and 48 of the 45 conduit pipes 24 while a substantially vertical disposed semi-circular passageway 49 formed in the block 23 connects the leg 50 of the conduit pipes 24 with the burner tip 26, which burner tip is threadably disposed in the forward and lower face portion of the block 23. The burner tip 26 is provided with a slot 51 for the emission of the vapor or gas.

To provide an efficient means to secure the 55 conduit pipes 24 in an angular position on the block 23 with respect to the burner tip 26 and to prevent the flame from the tip impinging directly upon the said pipes, the forward and upper portion of the block 23 is beveled to receive the retaining plate 25.

The plate 25 is provided with a plurality of holes 52 for the reception of the rear ends of the conduit pipes 24, the said ends being flared or expanded and being adapted to 60 seat in countersunk portions of the holes 52

formed on the inner side of the plate 25, as shown more clearly in Fig. 8. The plate 25 is fixedly secured to the block 23 by cap screws 53.

70 In practice I have found it practical to gradually increase the diameter of the longitudinal axial passageway or mixing chamber 55 in a forward direction from the rear end of the rearmost tubular member 19 to a point adjacent the connecting nipple 21 to 75 facilitate the suction action of the jets of steam or air on the fluid fuel in drawing the same from its source of supply and also to expedite the breaking up and mixing of the fuel with the steam or air prior to its vaporization and combustion.

To start the burner the door 41 is opened and a piece of oiled waste or other suitable material is placed upon the burner tip 26 and ignited to preheat the conduit pipes 24, 80 the door 41 is then closed to insert the burner within the fire-box, the fluid fuel control valve 16 is opened, the steam control valve 18 is also opened admitting steam into the chamber 32 and the annular passageway 30, 90 said steam passing therefrom at a high velocity through the grooves 35 in the members 19 into the passageway or mixing chamber 55 in the form of jets thereby creating a suction therein in a forward direction, as indicated by the arrows in Fig. 2, which suction will draw the fluid fuel from its source of supply into the mixing chamber where it is broken up by the said jets and thoroughly mixed with the steam or air prior to being 100 carried by the velocity of the steam into the conduit pipes 24.

As the conduit pipes 24 become heated the fuel contained therein is vaporized and passes to the burner tip 26 where it is ignited by the burning oiled waste.

105 The valves 16 and 18 may be regulated to obtain the amount of fuel and the suction required to maintain a flame of the desired intensity as will be readily understood.

110 From the foregoing description taken in connection with the accompanying drawings, the advantages of the construction and of the method of operation will be readily understood by those skilled in the art to which the invention pertains, and while I have described the principle of operation of the invention, together with the device which I now consider to be the best embodiment thereof, I desire to have it understood that the device shown is merely illustrative and that such changes may be made when desired, as are within the scope of the following claims.

115 What I claim is:

120 In combination with an oil burner, of a vacuum jet oil feed mechanism comprising a plurality of vacuum jets adapted to be secured together in end to end relation, each 125 of said jets comprising an outer casing pro-

vided with a cylindrical passageway that is counterbored at each end to form a seat, a tubular member having a perforated flange on one end disposed concentrically within 5 said passageway and adapted to fit within said seat, said tubular member being of less diameter than said cylindrical passageway whereby an annular passageway is formed therebetween and having one of its ends in-
10 ternally flared in a rearward direction, another tubular member having a perforated flange on one end adapted to fit within the said seat on the opposite end of said casing, said tubular member being of substantially
15 similar diameter of the first named tubular member and having one of its ends externally tapered and fluted and adapted to be

projected within the flaring end of the first named tubular member in concentric relation thereto to form a plurality of apertures of 20 relatively small area therebetween, an intake conduit for fluid fuel connected with the inlet end of said tubular members, controlling means interposed in said intake conduit, a supply pipe adapted to conduct fluid under 25 pressure into the said annular passageway, controlling means interposed in said supply pipe, and a delivery conduit connecting the outlet end of said tubular members with said burner. 30

In witness whereof, I hereunto subscribe my name this 10th day of April, A. D. 1920.

THOMAS L. DAVENPORT.
